CLEANER FOR IMPLEMENT WHEELS

Edd Roddel, Parker, S. Dak.

Application November 2, 1931. Serial No. 572,706

2 Claims. (Cl. 280—158)

My invention relates to improvements in cleaners for implement wheels, and particularly to a device of this character intended and adapted for use on tractors and other implements, to clean 5 dirt and trash from the front or rear wheels thereof, or both.

An object of this invention is to provide a structure of this character, in the nature of an attachment, which can be readily and expeditiously 10 installed and removed at the will of the user.

Another object is to so construct and mount the parts that portions of the structure are yieldable to prevent damage or breakage when the 15 implement is operating under subnormal conditions, as for instance, when backing.

Still another object is to provide a device of 20 this character of simple and inexpensive construction that can be installed without the use of special tools or the aid of a specially skilled mechanic, and that will prove efficient and durable in operation.

With the above and other objects in view, which 25 will be apparent to those skilled in the art, my invention includes certain novel features of construction and combinations of parts which will be hereinafter set forth in connection with the drawings.

In the drawings:

Figure 1 is a view in side elevation showing 30 one adaptation of my invention in connection with the front wheels of an implement.

Fig. 2 is a view in perspective of the structure 35 illustrated in Fig. 1.

Fig. 3 is an enlarged fragmentary sectional view 40 to better show the scraper mounting.

Fig. 4 is a view similar to Fig. 1 illustrating a modified construction particularly adapted for use upon the rear wheels of an implement.

Fig. 5 is a perspective view to better illustrate 45 the structure shown in Fig. 4.

Fig. 6 is a view in perspective showing a modified form of scraper blade.

As the parts are illustrated in Fig. 1, the wheel 50 1 has a rib 2, around the tread thereof and this wheel is mounted on an axle 3 which is associated with the spindle 4. To all intents and purposes, this structure is of standard construction and the structure will of course be varied with different types and makes of tractors and other implements.

The supporting member 5 is secured at its 55 forward end to be rigidly mounted in connection with the shaft 3 by means of a stud bolt 6, or other suitable fastening. A brace 7 is connected at one end with said supporting members 5 and

has its free end inclined upwardly and terminating in a fork or yoke 8 to fit the spindle 4. A shackle 9 is provided to be fitted around the spindle 4 and is connected with the brace 7 by means of a bolt 10, or other suitable fastening. 60 With the mounting as above set forth the supporting member 5 is secured in place with its free end extending rearwardly and adjacent to the tread of the wheel 1.

The rearward end of supporting member 5 is 65 formed as upwardly extending arm 11 and rocker arms 12 and 13 are mounted on opposite ends of the supporting member 5 by means of pivot pin or bolt 14 to be disposed for swinging movement adjacent to the arm portion 11. A cross bar or head 15 is secured upon these rocking levers 12 and 13 to extend on opposite sides of the supporting member 5 and a spring 16 is connected with the supporting member 5 and with the rocking levers 12 and 13 to normally 75 swing the same to a position in which the cross bar or head 15 is urged toward the arm 11. Scraper blades 17 are mounted on this cross bar or head 15 with their scraping edges 18 disposed downwardly to lie adjacent to or against the 80 tread face of the wheel 1, and an adjusting screw 19 is provided through arm 11 to make and retain desired adjustments to dispose the scraper blades 17 in the position for most efficient operation. 85

As illustrated in Fig. 2 the cross bar or head 15 can be extended on both sides of the supporting member 5, as for instance, where two wheels are mounted in close proximity on the 90 axle 3, and then two blades can be mounted on each end of this bar or head 15 to scrape the dirt of each wheel on each side of the rib 2, the blades being spaced as indicated at 20 so that the rib can travel in this space.

With the structure as set forth above, the position of the scraping blades with respect to the wheel tread can be adjusted and this adjustment will be retained through the resilient force exerted by spring 16. When the implement is traveling in a forward direction the scraping edge 18 will serve to scrape the wheels to remove dirt, trash and the like, and when the direction of movement of the wheels 1 is reversed, as for instance, when the tractor or implement is being 100 backed, the spring 16 will yield to permit sufficient clearance between the blade 17 and the wheel 1 so that the parts will not be bent, broken or otherwise damaged.

As the parts are illustrated in Fig. 4, the wheel 110 21 has a plurality of hobs or cleats 22 extending

from the tread face thereof in two circumferential lines, in the present instance shown as being staggered. With this arrangement it is desirable that the scraper blade be in the space 5 between the two circumferential lines of hobs or cleats, so that dirt or trash packing upon the tread surface will be scraped out with a gouging and chisel-like action, thus insuring a maximum efficiency in breaking packed material 10 from between the hobs or cleats 22.

As here illustrated, the supporting member 23 is bolted or otherwise secured upon the drum 24 of the axle, or upon other suitable portions of the implement structure, and this supporting member 15 23 is extended rearwardly and curved downwardly so that it terminates adjacent to the wheel rim, preferably at a point somewhat below the center of axle 25. A brace member 26 is secured at one end to the supporting member 20 23 and at its other end to the drum 24, or other suitable portion of the implement, and the supporting member 23 is thus given a substantially rigid mounting. An arm 27 is provided to extend laterally from the outer end of the supporting member 23 and is provided with openings to receive bolts 28, or other suitable fastenings by which the scraper blade 29 is secured in place. This scraper blade 29 is positioned to be in the space 25 30 between the circumferential rows of hobs or cleats 22 and the scraping edge 30 thereof is properly adjusted to a position to accomplish the most efficient operation.

In Fig. 6 I have illustrated a slightly modified form of scraper 31 and as here shown the scraping blade 32 is at one end and a plurality of openings 33 are provided at spaced points through the scraper adjacent the other end to permit adjustments in the mounting with respect to the supporting member. This same construction can be employed in connection with scraper blades 17 and 29. The blade 31 has a curved scraper arm 34 extending upwardly on the upper side and terminating in a scraper edge 35. The arm 34 is yieldable with respect to the 45

blade 31 and is so disposed that it will be in proximity to the tread surface of the wheel to loosen dirt or trash as the tractor or implement is backed.

While I have herein shown and described only certain specific embodiments of my invention and have set forth only certain possible modifications in the construction and arrangement of the parts and in the manner of application and of mounting the same, it will be appreciated that many changes and variations can be made in the form, construction, arrangement, assembly and mounting of the parts, without departing from the spirit and scope of my invention. 80 85 90 95 100 105 110 115 120 125 130 135 140 145 150

I claim:

1. A cleaner for implement wheels comprising, a supporting member to be mounted upon an implement with a portion thereof extending adjacent to the tread of the wheel, a brace member including yoke means to engage with a portion of the implement structure associated with said supporting member to hold the outer end thereof in substantially rigid mounting, a scraper blade swingably mounted at the outer end of said supporting member, means normally resiliently swinging said scraper blade to bring its edge against the tread of the wheel, and adjustable means carried by the supporting member operatively associated with the scraper blade to adjust and stop swinging movement thereof toward the tread of the wheel. 100 105 110 115 120 125 130 135 140 145 150

2. A cleaner for implement wheels comprising, a supporting member mounted upon an implement with a portion thereof extending adjacent to the tread of a wheel, a scraper blade swingably mounted by said supporting member, a spring normally resiliently swinging said scraper blade to move the edge thereof toward the wheel tread, and an adjusting bolt carried by the supporting member to stop and limit swinging movement of the effective edge of the scraper blade toward the wheel tread. 110 115 120 125 130 135 140 145 150
